(57) **CLAIM**

What is claimed is the ornamental design for a wire connector, as shown and described.

DESCRIPTION

FIG. 1 is a perspective view of a wire connector showing our new design;

FIG. 2 is a reverse perspective view thereof;

FIG. 3 is a top plan view thereof;

FIG. 4 is a bottom plan view thereof;

FIG. 5 is a first side elevational view thereof; and,

FIG. 6 is a second side elevational view thereof.
